UNITED STATES PATENT OFFICE.

RICHARD FELDHEIM, OF BARMEN, GERMANY.

WOVEN SKIRT-HOLDER.

1,100,868.

Specification of Letters Patent. Patented June 23, 1914.

Application filed May 26, 1913. Serial No. 769,965.

To all whom it may concern:

Be it known that I, RICHARD FELDHEIM, of Südstrasse 11, Barmen, Rhenish Prussia, Germany, have invented a new and useful 5 Woven Skirt-Holder, of which the following is a specification.

The object of my invention is a woven fabric and particularly a band or ribbon for ladies' dresses such as blouses and skirts 10 for instance serving as a holder for the said blouse or skirt and preventing the same from sliding or slipping, the novelty of my invention consisting in providing the band or ribbon with strips of pile such pile forming 15 an elastic and strong contact with the respective dress with the result that no sliding or slipping can take place.

My invention is fully shown on the accompanying drawing on which—

20 Figure 1 is a top view of the fabric. Fig. 2 is a cross section along line I—I of Fig. 1. Fig. 3 shows the application of the fabric.

Similar letters of reference indicate corresponding parts.

25 My fabric is composed of a band or ribbon *a* which may be woven of any suitable material size and in any desired color and binding adapted to be sewed to the top portion of a skirt *c* or to a blouse or employed 30 as a girdle. On said band or ribbon are arranged strips *b* which consist of pile and

said pile may be woven, sewed or glued on said band or ribbon so that it forms a part thereof.

It will be obvious that the pile forming an 35 elastic but close contact with the blouse or skirt will not permit any slipping or sliding of the respective part.

The pile strips *b* may be arranged in any other suitable configuration and may extend 40 either from one or both sides.

Having thus described my invention, I claim as new and desire to secure by Letters Patent:

1. In a woven skirt holder, a band of ribbon secured to a garment, said band having strips of pile, a strip of ribbon secured to a part of a garment overlapping the first mentioned garment and having strips of pile lying on the strips of pile of the first mentioned strip for retaining the garments against displacement. 45 50

2. An antislipping skirt band comprising a woven fabric, strips of pile secured to the fabric and arranged to form alternating rows 55 of pile projecting above the surface of the fabric substantially as described.

RICHARD FELDHEIM. [L.S.]
